COMBINATION SUPPORT AND REST FOR AN ELECTRIC IRON

Edna M. Linscheid, 3701 E. Funston,
Wichita, Kans. 67211

Filed Apr. 11, 1966, Ser. No. 1,837

Term of patent 14 years

(Cl. D49—6)

FIG. 1

FIG. 2

FIG. 3

FIG. 4

FIG. 5

FIG. 6

FIG. 7

FIGURE 1 is a side view of a combination support and rest for an electric iron embodying my new design.

FIGURE 2 is a front view thereof.

FIGURE 3 is a top plan view thereof.

FIGURE 4 is a bottom view thereof.

FIGURE 5 is an enlarged fragmentary side view thereof.

FIGURE 6 is an enlarged fragmentary top view thereof.

FIGURE 7 is an enlarged fragmentary rear end view thereof taken from the lower right-hand corner of FIGURE 3.

The broken line showing of the iron in FIGURE 1 and the partial showing thereof in FIGURE 5 are for illustrative purposes only.

I claim:

The ornamental design for a combination support and rest for an electric iron, as shown and described.
